UNITED STATES PATENT OFFICE

JOHN J. STRANG, OF KANSAS CITY, MISSOURI

DESIGN FOR A COMBINATION RADIO AND CLOCK CABINET

Application filed October 20, 1930. Serial No. 37,320. Term of patent 14 years.

To all whom it may concern:

Be it known that I, JOHN J. STRANG, a citizen of the United States, residing at Kansas City, in the county of Jackson and State of Missouri, have invented a new, original, and ornamental Design for Combination Radio and Clock Cabinets, of which the following is a specification, reference being had to the accompanying drawings, forming part thereof.

Fig. 1 is a front elevational view of a combination radio and clock cabinet.

Fig. 2 is a side elevational view of a combination radio and clock cabinet.

I claim:

The ornamental design for a combination radio and clock cabinet, as shown.

JOHN J. STRANG.
